UNITED STATES PATENT OFFICE.

SAMUEL J. ZINGMAN, OF NEW YORK, N. Y.

COMBINATION LOCK.

Application filed June 17, 1922. Serial No. 568,954.

To all whom it may concern:

Be it known that I, SAMUEL J. ZINGMAN, a citizen of the United States, residing at New York city, in the county of New York and State of New York, have invented certain new and useful Improvements in Combination Locks; and I do hereby declare the following to be a full, clear, and exact description of the invention, such as will enable others skilled in the art to which it appertains to make and use the same.

This invention relates to improvements in combination locks and has for one of its objects the provision of a device of this character whereby the shackle thereof may be locked and unlocked without the use of a key.

Another object of this invention is to provide a body adapted to slidably receive the shackle and having a plurality of locking elements or tumblers rotatably mounted thereon which may be so manipulated as to lock the shackle in said body or free the same therefrom.

A further object of this invention is to provide the locking elements on tumblers with double spaced walls having slots therein adapted to be aligned to permit a portion of the shackle to slide therethrough and which may be moved to offset or disalign the slots thereof to prevent the withdrawal of the shackle from the body.

A further object of this invention is the provision of means for moving the double walls in relation to each other so that the combination of the device may be readily changed when desired.

A still further object of this invention is the provision of a combination lock of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my in-

vention, reference is to be had to the following description and accompanying drawing, in which:—

Figure 1 is a front elevation of a lock 55 constructed in accordance with my invention,

Figure 2 is a vertical sectional view of the same,

Figure 3 is a transverse sectional view 60 taken on the line 3—3 of Figure 2,

Figure 4 is a similar view taken on the line 4—4 of Figure 2 looking in the direction indicated by the arrow, and

Figure 5 is a fragmentary elevational 65 view of a portion of the shackle.

Referring in detail to the drawing, the numeral 1 indicates an elongated body having formed upon one end a circular closing plate 2 to which is formed one end of a shackle 3. The shackle 3 consists of a pair of substantially L-shaped sections 4 and 5. The section 5 has one arm portion thereof formed integrally with the end closure plate 2 while its other arm portion is of hollow 70 formation as clearly illustrated in Figure 2 to slidably receive a reduced extension 6 formed upon the L-shaped section 4 of the shackle 3. The other arm portion of the section 4 has formed thereon an end closure 75 plate 7 on which is formed a shank 8 having a plurality of spaced bits 9. The elongated body 1 is provided with a slot 10 that opens out through the face thereof to slidably receive the shank 8 and permit the bits 9 to project beyond the face thereof for engagement with a plurality of locking elements or tumblers 11.

The locking elements or tumblers 11 each 80 consists of a pair of double spaced walls 12, each wall consisting of plates or disks 13 and 14. The disks or plates 13 are of a greater diameter than the plates or disks 14 and have mounted upon the peripheries thereof a band 15 on which is applied various 85 characters for the purpose of aiding in solving the combination of the device. The disks or plates 13 and 14 are each provided with circular openings to receive the body 1 so they can rotate freely thereon. The 100 plates or disks 13 of each of the locking elements or tumblers 11 are provided with a

plurality of spaced slots 15' that open outwardly in the central opening that receives the body 1. The plates 14 are each provided with a slot 16 which is adapted to be brought into registration with any one of the slots 15' of the plates 13 so that a bit 9 can pass through the plates 13 and 14 and be positioned between the double walls 12, as clearly shown in Figure 2.

10 The plates or disks 13 are each provided with a substantially circular groove or slot 17 that extends substantially about said disks or plates 13 and slidably receives pins 18 formed upon the plates 14. The pins 18 have formed thereon heads 19 that frictionally engage the outer faces of the plates 13 to prevent accidental movement of the plates 14 in relation to the plates 13, when the device is in use.

20 In assembling the device, the sections 4 and 5 of the shackle 3 are moved apart so that the locking elements or tumblers 11 may be readily inserted upon the body in close proximity to each other. The locking elements or tumblers are held upon the body 1 by means of a spring actuated pin or plunger 18 carried by the body so that they cannot become detached from the body when the lock is open. To lock the device, the sections 4 and 5 of the shackle 3 are moved in the direction of each other causing the shank 8 to move within the slot 10 of the body and the bits 9 to pass through the alining slots 15' and 16 of the plates 13 and 14 to position themselves between the walls of the locking elements or tumblers 11. The locking elements or tumblers 11 are then rotated about the body 1 so as to disaline the slots of the plates 13 and 14 from registering with the bits 9 thereby preventing the shackle 3 from being opened. When the shackle 3 is in a locked or closed position as illustrated in Figures 1 and 2, the end closure plate 7 is in close proximity to the locking elements or tumblers 11 so that it is impossible to actuate the spring plunger 18 to disarrange or remove them from the body. To unlock the device, the locking elements or tumblers 11 are rotated on the body 1 so as to aline the slots in the plates 13 and 14 with the bits 9 and the sections 4 and 5 of the shackle may then be readily separated so as to disengage the shank 8 from the body 1.

30 In order to change the combination of the locking elements or tumblers 11, they are removed from the body 1 by pressing inwardly upon the pin 18 and the plates 14 are moved in relation to the plates 13 so that the slots of the plates 14 will register with other slots of the plates or disks 13 thereby changing the combination of the device.

40 While I have shown and described the preferred embodiment of my invention, it will be understood that minor changes in construction, combination and arrangement

of parts may be made without departing from the spirit and scope of the invention as claimed.

Having thus described my invention, what is claimed is:

70 1. A combination lock comprising a telescopic shackle, a body carried by one section of the shackle and having a groove opening out through the face and one end thereof, a shank formed on the other section of the shackle, bits formed on said shank and extending beyond the face of the body, spaced pairs of disks rotatably mounted on the body and each having a plurality of slots to receive the bits, bands secured to the peripheries of the disks, and a second disk for each one of each pair of disks, said second disks mounted on the body between the first named pairs of disks and each having a slot adapted to be registered with any one of the slots of the first named disks. 75 80 85

90 2. A combination lock comprising a telescopic shackle, a body carried by one section of the shackle and having a groove opening out through the face and one end thereof, a shank formed on the other section of the shackle, bits formed on said shank and extending beyond the face of the body, spaced pairs of disks rotatably mounted on the body and each having a plurality of slots to receive the bits, bands secured to the peripheries of the disks, a second disk for each one of each pair of disks, said second disks mounted on the body between the first named pairs of disks and each having a slot adapted to be registered with any one of the slots of the first named disks, said first named disks each having a circular groove, and pins formed upon the second named disks and extending through the grooves for moving the second named disks in relation to the first named disks to change the combination. 95 100 105

110 3. A combination lock comprising a telescopic shackle, a body carried by one section of the shackle and having a groove opening out through the face and one end thereof, a shank formed on the other section of the shackle, bits formed on said shank and extending beyond the face of the body, pairs of spaced disks journaled upon said body and having slots to receive the bits to position said bits therebetween, bands carried by the peripheries of the pairs of disks, closing disks carried by the sections of the shackle, and a spring actuated pin carried by the body at one end thereof and adapted to prevent accidental displacement of the disks from the body. 115 120

125 4. A combination lock comprising a telescopic shackle, a body carried by one section of the shackle and having a groove opening out through the face and one end thereof, a shank formed on the other section of the shackle, bits formed on said shank and ex- 130

tending beyond the face of the body, spaced pairs of disks rotatably mounted on the body and each having a plurality of slots to permit passage of the bits to a position between 5 disks of the respective pairs, bands secured to the pairs of disks, a second disk for each one of each pair of disks, said second disks mounted on the body between the disks of the first named pairs of disks, said second 10 disks each having a slot adapted to be brought into registration with any one of the slots of the first named disks, said first named disks each having a substantially circular groove, pins formed on the second

named disks and extending through the 15 groove for moving the second named disks relative to the first named disks to change the combination of the lock, and said pins each having a head to frictionally engage the grooved disks at the grooved portions 20 thereof to prevent accidental relative movement of the disks.

In testimony whereof I affix my signature in presence of two witnesses.

SAMUEL J. ZINGMAN.
